UNITED STATES PATENT OFFICE

LEE L. BROOKS, OF MIDLAND, TEXAS

TANK CONSTRUCTION

Application filed September 10, 1930. Serial No. 480,873.

My invention relates to storage tanks for storing crude petroleum, and more particularly to means for enclosing and protecting the metallic binding elements of a tank from contact with the acid content of the petroleum; the principal object of the invention being to prevent disintegration of the binding elements and thereby prolong the serviceability of the tank.

10 In accomplishing this and other objects of my invention, I have provided improved details of structure, the preferred form of which is illustrated in the accompanying drawing, wherein:

15 Fig. 1 is a top plan view of a tank constructed according to my invention, shown broken away for better illustration of my improvements.

Fig. 2 is a central vertical section through 20 the tank on the line 2—2, Fig. 1.

Fig. 3 is a fragmentary sectional view of one of the supporting columns, particularly illustrating its mounting on the bottom of the tank.

25 Fig. 4 is a fragmentary sectional view of the top of the tank showing a supporting column in abutment therewith.

Fig. 5 is a transverse section through one 30 of the assembled columns.

Referring in detail to the drawing:

1 designates a tank of conventional construction except for my improvement, having circular side walls 2 formed by a plurality of vertical staves 3 notched at their upper

35 and lower ends 4 and 5 for engagement with the peripheries 6 and 7 of the bottom floor 8 and the head or deck floor 9 respectively, the staves being urged to sealing relation with one another and secured against the floor and deck by adjustable tie rods 10 to form a fluid-tight enclosure for containing petroleum and the gases which may emanate therefrom.

Extending vertically through the tank in spaced relation with the side walls 2 are tie 45 rods 11 having threaded ends 12 and 13 extending through clamping plates 14 and 15 on opposite sides of the bottom 8 and deck 9, the clamping plates being arranged transversely over the deck boards 16 and bottom 50 floor boards 17, and clamped thereon by nuts

18 on the rods, thereby reinforcing the floor members and providing a suitable thickness for properly anchoring the tie rods.

When a tank of this construction is employed for storing crude petroleum, the tie rods 11 are subjected to the decomposing action of certain acid components of the oil which eventually weaken the rods and render the tank unserviceable until repairs or replacements are made.

In overcoming such injury to the rods, I provide the tank with support columns 19 preferably constructed of wood and of sufficient length to abut snugly between the clamping plates 14 and 15 on the bottom 8 and deck 9 of the tank. The columns 19 are preferably square in cross section, each having a through longitudinal slot 20 in one side thereof and extending radially outward from the axial center of the member for receiving a tie rod 11, so that the column may be placed on a tie rod previously assembled in the tank, and the nuts 18 may then be adjusted on the rods for clamping the columns between the clamping plates 14 and 15, the columns serving to space and support the deck 9 in proper relation with the bottom floor 8.

With the columns 19 clamped in position on a tie rod, a sealing strip 21 of suitable material is inserted in the slot 20 and properly sealed therein to prevent contact of the petroleum with the tie rods when the tank is in use.

From the foregoing it will be apparent that a tank equipped with my improved support columns will not be subject to the frequent repair otherwise necessitated by the above stated causes, and a considerable saving in cost of maintenance will be effected.

What I claim and desire to secure by Letters Patent is:

1. A tank of the character described for containing corrosive fluid under pressures varying above and below atmospheric pressure, including a side wall and a top and bottom wall comprising a plurality of juxtaposed members having their ends supported by the side wall, clamping members extending across the inner faces of said members,

complementary clamping members extending across the outer face of said members in superimposed relation with the first clamping members, tie rods extending through the 5 top and bottom walls and through said clamping members, means on said rods arranged to retain the clamping members in clamping relation with said top and bottom wall members and to retain the top and bottom walls from 10 bulging outwardly when pressure within the tank exceeds atmospheric pressure, and shielding members enclosing the rods from the corrosive action of fluid contained in the tank and arranged for forming columns to 15 support the top wall when the pressure within the tank drops below atmospheric pressure and to relieve the rods of compression forces.

2. A tank of the character described for containing a corrosive fluid under pressures 20 varying above and below atmospheric pressure, including a side wall and a top and

bottom wall having their peripheries supported by the side wall, clamping members extending across the inner faces of the top and bottom walls, complementary clamping members extending across the outer face of the walls in superimposed relation with the first named clamping members, a tie rod extending through the top and bottom walls and through said clamping members, means arranged on said rod to retain the clamping members in clamping relation with said top and bottom walls and prevent the top and bottom walls from bulging outwardly when the pressure within the tank exceeds atmospheric pressure, and a shielding member covering said rod and arranged to form a column for supporting said top wall when the pressures in the tank drop to and below atmospheric pressure.

In testimony whereof I affix my signature. 85
LEE L. BROOKS.
